Miami, Fla.

Application July 19, 1933, Serial No. 681,110

7 Claims. (Cl. 45—59)

The present invention relates to book or magazine holders or supports or easels and its aim is to provide a structure of this character which is simple in construction, which is efficient in use, which is relatively inexpensive to manufacture, which presents a pleasing appearance, and which can be folded into small compass when not in use.

In general, the novel and improved appliance includes a flat seat-member which may be positioned either under or on top of a seat-cushion of a chair, and a foldable or collapsible book or magazine rest or shelf having supporting legs adapted to be demountably or detachably accommodated at their lower ends in exposed sockets in the seat-member, the structural features being such that the occupant of the chair having the apparatus applied thereto may peruse the contents of the book, magazine or the like resting on the shelf or ledge of the device with comfort and satisfaction, the structure as a whole having adequate adjustment characteristics to position the book or its equivalent in proper position for reading with facility.

To the attainment of these and other desirable and beneficial aims and purposes, a present, preferred embodiment of the invention has been provided and this has been illustrated in detail in the accompanying drawings, forming a part of this specification, and to which reference should be had in connection with the following description.

For simplicity and ease of understanding of the specified desirable incorporation of the invention in physical form and a modification thereof also shown in the drawings, like reference numerals have been used throughout the several views of the drawings to designate the same parts of the structure.

In these drawings:—

Figure 1 is a perspective view of the complete appliance showing the supported book or magazine in dotted lines;

Figure 2 is an enlarged, plan or face view of the book-like shelf in open or flat condition, showing the supporting legs or standards in full lines in folded positions and indicating in dotted line the manner of unfolding the legs or posts into operative condition;

Figure 3 shows the appliance, except the associated seat-member, in perspective, in completely folded relation;

Figure 4 is an enlarged, fragmentary, detail section on line 4—4 of Figure 3;

Figure 5 is a similar section on line 5—5 of Figure 2;

Figure 6 is a view analogous to that of Figure 5, except that the book-like shelf-member is shown folded as in Figure 3;

Figures 7 and 8 depict one of the friction hinge joints of the legs or posts; and

Figure 9 is a partial view, similar to the showing in Figure 2, of a modified structure.

Referring to these drawings, it will be readily perceived and understood that the new and advantageous book or magazine holder includes a flat or plane seat-member 11 of suitable size and appropriate shape to fit under the cushion of a chair or the like, although in some cases, such element may be satisfactorily used by laying it on the top of the chair-seat without any cushion superposed thereon.

In either instance, such seat-member is securely and firmly held in place by the weight of the reader or user being imposed thereon, either through the cushion of the chair-seat or directly.

Such part 11 may be made of any appropriate material, but, in the present case, it is formed of a metal frame covered with suitable fabric.

Member 11 at its front edge has a pair of widely-spaced, forwardly-extended socket-members 12, 12, each having an upright hole 13 therethrough designed and intended to demountably receive the lower ends of the standards or legs referred to more specifically hereinafter.

Obviously, in order to perform their intended functions, these socket-members must project beyond the front of the chair-seat cushion when the part 11 is in correct operative position.

The elevated book or magazine support or shelf, designated as a whole 14, is foldable or collapsible, and when closed, as shown in Figure 3, it has the appearance of a book, and it may therefore be present in a library or elsewhere without conspicuously disclosing the purpose which it may fulfil.

Such member 14 is composed of a middle narrow section 15, corresponding to the back of a book, to which two, opposite, side sections or leaves 16, 16 are hinged at 17, 17, the three sections being generally covered by fabric of a nature to make the structure look like a book, the appliance desirably being supplied with one or more external legends to make the deception or imitation more complete.

At its lower edge, each side-section has a bracket 18 mounted thereon with a straight edge 19 designed to engage and bear on the front face of the back 15 when such book-like structure is

closed, as portrayed in Figure 6, to prevent such sides from closing beyond a parallel relation to one another.

To form a lock to hold these three sections 15, 16, 16 rigidly in the same plane, as depicted in Figures 1, 2, and 5, a pair of parallel links 21 are rockingly mounted on one bracket 18 at 22, and a pair of links 23 are in like manner rockingly mounted on the companion bracket at 24, the two sets or groups of links being hinged together at 25, one of such links having a finger-piece 26, and all of the links having enlargements 27.

To lock the shelf elements 16 against turning on their hinges, after the shelf has been flattened out, the operator pushes the links toward the back 15 until the parts 27 strike such back, at which time the links will have passed slightly beyond dead-center and will act as an efficient lock.

20 To fold the shelf 15, 16, 16, by means of the finger-piece 26, the links are pulled forwardly beyond dead-center, thus terminating their locking function.

The manner in which this locking and unlocking is accomplished will be easily understood from an inspection of the illustrations in Figures 5 and 6.

Referring to Figure 2, it will be seen that each section 16 near the center portion of its edge opposite its hinge has a bifurcated hinge-bracket 28 rockingly accommodating the inturned end portion of a rod 29, which, while capable of oscillation in the hinge-bracket, is restrained or restricted in so doing by means of imposed friction as by a nut 31 on the end of the rod and one or more friction-washers 32 interposed between the nut and the adjacent end of the hinge portion of the bracket.

40 The other end of each rod 29 is hinged at 33 to another rod section 34, the hinge structure applying a substantial friction to the two rockingly-connected parts so that they will retain their positions, unless forcibly swung with relation to one another by overcoming the applied friction.

In similar manner, each rod section 34 is hingedly united at 35 to a tapered stud or post 36 adapted and designed to be removably fitted in the corresponding socket 13.

45 It should be noted that the two hinge-pins at 33 and 35 are at right-angles to one another so that each section 34 may swing in one plane in relation to the part 29 and the section 36 may be rocked in a plane at right-angles thereto.

50 A detailed description of one hinge 35 will suffice for all, as they are practically alike or at least work on the same principle.

Referring to Figures 7 and 8, it will be observed that the rod 34 has a collar 37 pinned thereon and that such collar has an apertured blade 38 through the hole in which the hinge-pin extends.

55 Rod 34 has another collar 39 thereon carrying an apertured blade 41 the hole in which receives pin 35, the rod, in addition, having a third collar 42 thereon equipped with a similar blade 43 likewise accommodating the hinge-pin.

60 Plug or post 36 has a shoulder or enlargement 44 limiting its insertion in the complementary socket, and it is also fitted with a collar 45 having an apertured blade 46 between the blades 38 and 41 and a collar 47 having a perforated blade 48 between the blades 38 and 43, the hinge-pin occupying the holes in blades 46 and 48.

75 Such hinge-pin 35 is in the form of a short bolt

equipped with a lock or spring washer 49 between the nut 51 of the bolt and the face of the adjacent blade.

By means of these overlapping and contacting blades and the associated bolt a suitable measure 80 of friction can be at all times exerted on the hinge to cause the parts thus joined together to maintain any desired angular relation until such relative position is intentionally changed.

In hinge 33 stops of any suitable character may 85 be used to preclude the rod sections 29 and 34 from rocking relatively to one another beyond the point of their longitudinal alignment.

90 In passing, it should be noticed that the top edge 52 of the flat shelf 15, 16, 16 is longer than the opposite lower edge 53 thereof in order to permit the lower half of the shelf to swing toward the user between the two supports 36-34-29, thus giving the shelf any desired degree of inclination.

95 Along their lower edges the shelf sections have aligned angle-bar ledges 54, 54 on which the lower edge of the book or magazine is designed to rest.

100 Also, the one bracket 28 is provided with a hinged clasp 55 rockingly mounted on the in-turned end portion of rod 29 in the space supplied by the bifurcated nature of the structure, the opposite end of the clasp being of hook form, as presented in Figure 4, to snap over the exposed 105 part of the inwardly-directed end section of the rod 29 mounted in the other bracket.

110 By this means the folded shelf may be readily maintained, as desired, in its closed-book form, and, of course, by releasing such clasp, the shelf 110 may be flattened out for use.

The improved book holder or easel is used in substantially this manner:

115 The seat-member 11 is placed under the seat-cushion of the chair, or, in some cases, it may be used on the top of the chair-seat when the latter is not equipped with such a cushion, but in either instance the sockets 13, 13 are exposed at the front of the seat.

120 Thereupon the reader sits on such cushion, or on the part 11, as the case may be, and he releases the clasp 55, opens up the book-like shelf 15, 16, 16, and locks the parts thereof flat or in the same plane by pressing on the finger or thumb piece 26, thereby rendering the toggle-lock 125 21-23 operative.

130 Then he swings the two rods 29, 29 on their hinge-brackets 28, 28, turns the rods 34, 34 into alignment with their companion rods 29, 29, inserts the two plugs 36, 36 in the seat sockets 13, 13, 135 bends the hinges 35, 35 to position the easel shelf at the desired distance from him, and then swings the now-rigid shelf 15, 16, 16 on the hinges 28, 28 to obtain its required slope or inclination.

140 Owing to the friction in all of the hinges, the parts will readily retain their adjusted positions, and the operator can read a book or magazine on the shelf with comfort and satisfaction.

145 The manner of folding the appliance will be readily understood from what precedes and no further description thereof is deemed necessary.

Instead of directly hinging the bent end of each rod 29 to the inside of the section 16, the hinge 145 128 (see Figure 9) of such end may be mounted on a shaft 228 to rock in a plane parallel to the shelf section, thus, in the folded condition of the supporting standards or legs, bringing the parts 29 well away from the upper edge of the folded shelf.

Although two embodiments of this invention have been set forth by way of description and illustration, it is to be understood that the invention, as defined by the appended claims, is not

5 necessarily limited to the details of the constructions and that more or less radical changes may be incorporated in the appliances without departure from the heart and essence of the invention and without the loss of any of its substantial benefits and advantages.

We claim:

1. In a reading-matter support, the combination of a substantially chair-seat-shaped base adapted to rest on a chair seat and having a pair 15 of spaced sockets, a book-like foldable shelf to support the reading-matter comprising a back and side-sections hinged to said back at its opposite edges, means to lock said shelf in flat open condition, standards having lower ends adapted 20 to be detachably accommodated in said sockets, hinges connecting the upper portions of said standards, and means to maintain the desired inclination adjustment of said shelf on said standards to the side-sections of said shelf, 25 thereby permitting adjustment of inclination of said shelf on said standards.

2. The structure presented in claim 1 in which said standards are foldable and adapted in their folded condition to be substantially wholly accommodated in the closed-book folded condition of said shelf.

3. In a reading-matter support, the combination of a base adapted to rest on a chair seat and having a pair of spaced sockets at its front, a 35 pair of standards having lower, intermediate and top sections, said lower sections being adapted to be demountably accommodated in said sockets, a shelf to support the reading-matter, hinges connecting said shelf to said standard top sections 40 permitting the shelf to be swung thereon to the desired degree of inclination, hinge-joints connecting said lower and intermediate standard sections permitting said shelf and the intermediate and top sections of the standards to be 45 rocked toward and from the occupant of the chair, and second hinge-joints between said intermediate and top sections permitting folding of said standards, the axis of each of said sec-

ond hinge-joints being at substantially a right-angle to the axis of the corresponding first hinge-joint.

4. The structure presented in claim 3 in which the top edge of the shelf is longer than the distance between said standards when the latter are in operative position and the lower edge of the shelf is shorter than said distance to permit the lower half of the shelf to be swung between said standards.

5. In a reading-matter support, the combination of a base adapted to rest on a chair seat and having a pair of spaced sockets at its front, a pair of standards having lower, intermediate and top sections, said lower sections being adapted to be demountably accommodated in said sockets, a book-like foldable shelf to support the reading-matter comprising a back and side-sections hinged to said back at its opposite edges, means to lock said shelf in flat open condition, 95 hinges connecting said shelf to said top standard sections permitting the shelf to be swung thereon to the desired degree of inclination, hinge-joints connecting said lower and intermediate standard sections permitting said shelf 100 and the intermediate and top standard sections to be rocked toward and from the occupant of the chair, and second hinge-joints between said intermediate and top standard sections permitting folding of said standards, the axis of each 105 of said second hinge-joints being at substantially a right-angle to the axis of the corresponding first hinge-joint, said standards in their folded condition being adapted to be substantially wholly accommodated in the closed-book 110 folded condition of said shelf.

6. The structure presented in claim 5 in which the top edge of said shelf is longer than the distance between said standards when the latter are in operative position and the lower edge of the 115 shelf is shorter than said distance to permit the lower half of the shelf to be swung between said standards.

7. The structure presented in claim 1 in which said base comprises a border chair-seat-shaped 120 frame covered with a flexible fabric.
